GUN

Joseph C. White, Wakefield, Mass., assignor to
 White Automatic Gun Corporation, Portland,
 Maine, a corporation of Maine

Application March 24, 1933, Serial No. 662,475
 In Great Britain April 11, 1932

21 Claims.

(Cl. 42-3)

My present invention relates to firearms and more particularly aims to provide an improved recoil-operated breech mechanism for self-loading military and other guns, said breech mechanism providing a high factor of safety and being relatively simple and compact in structure and of light weight.

In the drawings, illustrating, by way of example, one embodiment of my invention,

Fig. 1 is a central longitudinal section through the breech mechanism, showing the parts in their position at the moment of firing;

Fig. 2 is a view corresponding to Fig. 1, but illustrating the parts in their full open position;

Fig. 3 is a partial side elevation of the receiver and a fixed part secured to the gun stock, the receiver being positioned as at the completion of its short recoil;

Fig. 4 is a view partly in horizontal section and partly in plan, substantially upon the line 4-4 of Fig. 1;

Figs. 5 and 6 are respectively a side elevation and a rear end view, partly broken away, of the breech block;

Fig. 7 is a side elevation of the intermediate member or link;

Figs. 8 and 9 are respectively a side elevation and a rear end view of the crank;

Fig. 10 is a view in perspective of an arm or link operatively connecting the crank and the actuator;

Fig. 11 is a detail view upon a larger scale showing a portion of the return mechanism seen at the lower right portion of Fig. 2;

Fig. 12 is a horizontal section on the line 12-12 of Fig. 1;

Figs. 13 and 14 are vertical sections on the lines 13-13 and 14-14 respectively of Fig. 12, looking in the direction of the arrows; and

Fig. 15 is a perspective of the stock abutment.

Referring first more particularly to Figs. 1 to 4, the gun comprises a barrel 1 threaded or otherwise fixed at the fore part of a receiver 2, the rear portion of which is closed by a removable plate 3. The barrel and receiver are slidably associated with the gun stock or frame, a portion of which is indicated at 4. A frame or stock abutment 5, seen separately in Fig. 15, is anchored in the stock as by means of the screws illustrated.

The breech mechanism as illustrated is a toggle-joint or crank structure comprising three main elements which are readily assembled or dismounted with respect to the receiver, as a

unit. These include a rectilinearly guided breech block proper 6, an intermediate pivoted element or link 7 and a rear pivoted element or crank 8.

The block 6 is provided with lateral ribs 9 riding in grooves 10 in the receiver (Figs. 2 and 4), whereby it is guided for reciprocating movement. The block carries a fulcrum pin 11 removably held in place by a spring pressed pin 12 whose spring 13 bears at its forward end against a plunger 14 engaging the extractor 15, thus serving as a spring for the latter. The fulcrum pin 11 of the block is received in a boss 16, Figs. 5 and 6, positioned between the forward ears 17 of the link 7, Fig. 7, the latter being apertured for reception of the fulcrum pin 11.

The link 7, which houses a portion of the firing train to be referred to, is pivotally associated, at its rear end, with the fore part of the crank 8, by means of the rear tongue or boss 18 of the link received between corresponding ears 19 of the crank, said boss and ears being apertured for reception of the toggle pin 20 previously mentioned. This pin is removably held in place by the key 21, Figs. 1 and 2, itself releasably pinned in position. The crank 8 in turn is pivotally positioned at its rear end in the receiver by the crank fulcrum pin 22, removably held in the receiver walls as by means of a spring element 23, the rear portion of which surrounds and seats in a groove in the fulcrum pin 22 while its fore portion engages and locks in place the screw plug 24, forming a housing for the spring 25 of the buffer 26.

In the closed or locked position of the breech mechanism parts, as shown in Fig. 1, the breech block, link and crank form in effect a single piece or unitary mass for closing the breech and transmitting the firing stresses directly to the receiver. Said main parts of the breech closure as a whole, that is, the breech block proper 6, link 7 and crank 8, are so constructed and arranged at their adjoining portions, and in relation to the receiver, that the pivot and fulcrum pins are relieved of the firing strains, the latter being transmitted to the receiver directly by the main elements themselves, independently of the pivot and fulcrum pins.

For this purpose abutting locking surfaces of substantial area are formed, concentrically with the fulcrum pin 11 of the block, between the breech block and the link, as indicated at 27, 27, Figs. 1, 2, 4, 5, and 7. Other large area locking surfaces are likewise provided between the link 7 and the crank 8, as indicated at 28, 28 by the dotted line in Fig. 1 and seen in full line in Figs. 55

4, 7, and 8, formed respectively at the sides of the link and at the front face of the bosses or ears of the crank, concentrically with the link and crank connecting or toggle pin 29.

5 The crank itself is further provided with solid and large area pressure-transmitting shoulders 29, formed concentrically with the crank fulcrum pin 22 and adapted to make abutting engagement with similarly formed opposed shoulders 30 on the receiver side walls, in the closed position of the parts; see particularly Figs. 1, 3, 4, 8 and 9. As indicated by the dotted lines at the right in Fig. 4, the crank fulcrum pin 22 has a clearance with respect to the crank. Hence, the breech pressure attendant on firing is transmitted directly to the crank and by the latter, through the interengaged large area surfaces 29, 30 to the receiver itself. Accordingly no shearing strains are placed upon the pivot or fulcrum pins, and particularly is the crank fulcrum pin 22 left free of such strains.

To assist in the breech opening effort, there is pivotally connected to the rear portion of the crank 8, at 31, an actuator link 32, shown separately in perspective in Fig. 10. This actuator link is in turn pivotally associated, by means of its cross piece 33, with an actuator 34.

The actuator 34 is slidably mounted in the lower rear portion of the receiver 2, the latter 30 being provided with ribs 35, Figs. 13 and 14, received in corresponding grooves or guideways at the sides of the actuator. The actuator in part houses the main counter-recoil or return spring 36, also the initial or auxiliary return spring 37, 35 as well as a pair of cushioning and breech opening spring-pressed plungers 38, see particularly Fig. 12. The springs 39 of the latter are removably housed in the actuator, wherein they are held in the screw plugs 40.

40 The actuator 34 includes a centrally disposed and rearwardly projecting tubular portion 41, closed sufficiently at its rear end to provide a rear abutment for the main return spring 36, which is received in said tubular portion 41. As 45 best seen in the detail Fig. 11, said return spring 36 bears rearwardly against a washer 42, which in turn is received against the rear of the tubular portion 41 of the actuator. Within the main action or return spring 36 is a floating sleeve 43 50 which assists in guiding the main spring 36 and also houses the auxiliary spring 37. The latter is positioned between a plunger 44, at its rear end, and a stud 45 received in and removably pinned to the sleeve 43 by the bayonet joint connection seen in Fig. 2. Said stud 45 is fixed in the adjacent depending portion of the receiver 2, Fig. 12, against which receiver portion the main spring 36 also bears at its fore end. The sleeve 43 has a head 46 at its rear end against which the 55 washer 42 will abut when the action spring is removed from the actuator, thereby keeping the spring from flying off from the sleeve 43, and conveniently but removably holding the parts together.

55 The rearward pressure and reaction thrusts of the action springs and of the actuator and its plungers, as well as any remaining rearward pressure of the receiver itself, are received directly by the frame or stock abutment 5 previously 60 mentioned, which is stationarily but removably anchored in the stock. Said abutment 5 is shown separately in perspective in Fig. 15. It includes the main forwardly facing, pressure-receiving surface 47, lateral guides 48 for sliding 65 co-operation with the actuator, a bore 49 for

sliding reception of the rearwardly projecting portion 41 of the actuator, and the closed rear wall 50 against which said rearwardly projecting portion of the actuator, and the parts housed therein, are adapted to abut. Said stationary 5 abutment 5 is provided with forwardly facing receiver-stops 51, engaged by a rear portion of the receiver at the end of its full recoil, which recoil, as hereinafter pointed out, is extremely short, being as herein illustrated but about $\frac{1}{4}$ inch total. Said rearmost or full-recoil position of the receiver relative to said abutment and the frame or stock is illustrated in Fig. 3. At the upper portion of this stationary abutment 5 are rearwardly facing shoulders 51 constituting forward or return stops for the receiver and its supported parts, at the end of the counter-recoil, said stops being then engaged by the rear plate 3 of the receiver, see Figs. 1 and 2. It will be noted that the length of the total recoil of 20 the receiver, being herein but about $\frac{1}{4}$ inch, is but a minor fraction of the length of the rifle cartridge. As the military cartridge intended for use with the rifle as illustrated herein, see Fig. 1, is approximately $3\frac{1}{4}$ inches long, which 25 is also approximately the length of the Springfield cartridge, the total recoil is but about $1\frac{1}{13}$ the length of the cartridge. The total recoil distance of the receiver is readily apparent in Fig. 2, for example, as indicated by the horizontal space between said rearwardly facing shoulders 51 of the abutment 5 and the rear plate 3 of the receiver.

Referring again to Figs. 1 and 2, the breech block 6 houses a firing pin 52 and also the ejector 53 including its spring 54 and spring housing 55. The link 7 carries the slideable striker 56 which is adapted, at the proper time, to make firing contact with the firing pin 52. The striker 56 is urged forwardly by the striker spring 57 and is 40 formed with a cocking notch 58 adapted to receive the nose of the sear 59 by which the striker is held in cocked position. The forward portion of the striker is formed with a cocking cam 60 co-operating with a cocking cam face 61 at the 45 rear of the breech block. As will be understood by comparison of the position of the parts in Fig. 2 with those of Fig. 1, the striker is cammed rearwardly, during opening of the breech parts, by the interaction of said cam faces 60 and 61. 50

The sear 59 is guided for vertical movement in the link 7, by suitable guides, including the depending portion 65 below referred to, and in part by the stud 62 extending through the sear and removably held in place by a lock plate 63. Below the stud 62 is a spring 64 housed in a hollow plunger or barrel portion 65 depending from the sear 59 and movably positioned in the link, said plunger and the sear itself thus being urged downwardly by said spring against one arm of a bell-crank lever 66 pivoted in the link 7. Said lever is prevented from rearward or counter-clockwise movement by the adjacent surface 66a of the link 7. Forward movement of the lower arm of the bell-crank lever 66 is adapted to elevate the sear 65 and release the striker, to fire the gun.

Any suitable form of trigger mechanism may be provided for actuating the sear 59 and the lever 66, such, for example, as in my copending applications Serial Nos. 419,318 and 576,666, now 70 Patents Nos. 1,907,164 and 1,907,163 dated May 2, 1933. Automatic cartridge supplying means is also contemplated, which likewise may be, for example, such as that of said previous applications. 75

The action of the gun is as follows:—

On ignition of the charge, the recoil mass, consisting of the barrel 1, the receiver 2, the toggle mechanism and actuator, commence to move rearwardly, as the bullet starts forward, with a velocity dependent on their combined weights. During the first part of this movement (represented by the gap of some $\frac{3}{8}$ of an inch shown at 67 between the face 68 of the actuator and shoulders 47 on the abutment 5) no event occurs except the pushing in of the plungers 38. It will be understood that the pressure locking surfaces, including the shoulders 29, 30 intermediate the crank and receiver, are so held together by the high chamber gas pressure that no movement to unlock can occur during the movement of the plungers 38. However, by the time the shoulders 47 of the abutment 5 have been contacted by the corresponding surfaces of the actuator face 68 sufficient time has elapsed to allow the bullet to leave the barrel and the chamber pressure to fall substantially to zero. The aforesaid recoiling mass, except the actuator, is still at this time free to move an additional $\frac{3}{8}$ of an inch or thereabouts and the pressure now existing between the abutment 5 and the spring plungers of the arrested actuator causes the link 32 (as its pivotal connection at 31 to the crank continues to recoil) to break the toggle upwards and to separate the pressure locking shoulders 29. As the explosion pressure resisting surfaces between the breech block, link and crank at 27, 28, and 29 are not now held frictionally the crank is free to swing upwardly and open the breech. The aforesaid $\frac{3}{8}$ of an inch of recoil movement between the actuator and the pivot 31 of the link 32 thus starts the crank through its opening arc of movement and the completion of this movement is in part brought about by the momentum of the mass of metal in the crank and the link assisted by the reaction of the springs of the plungers 38, the faces 47 and 68 moving apart as the breech opening is thus completed. The limit of the swing of the crank is determined by a shoulder 69 of the receiver 2, the crank being cushioned by the spring buffer 26 on the crank contacting with the corner 70 of the said receiver shoulder 69. The empty shell is extracted from the chamber by the extractor 15 on the breech block. When the breech block 6 has moved rearwardly the length of the empty cartridge case the latter is expelled from the receiver by the spring controlled ejector pin 53 also carried in the breech block. The crank 8, the link 7 and the breech block 6, by a return or straightening movement, due to the actuator spring 36, now feed a live cartridge into the chamber, and the gun can be fired again by the trigger mechanism (not shown) which connects with the bell crank lever 66. This lever 66 pushes the sear 59 upwardly, releasing the striker 56. The striker 56 hits the firing pin 52 and the primer is exploded. The striker 56 is rectilinearly guided along the link 7 which carries it and is cocked as the toggle breaks by the cocking cam face 61 formed on the breech block and acting as the toggle is straightened again as a safety cam preventing premature firing.

Easy separation of the locking surfaces 29 for opening the breech when the chamber gas pressure has been dissipated is provided for by the previously mentioned suitable degree of looseness of fit of the fulcrum pin 22 with respect to the crank. This looseness while not affecting the service of the pin as a pivotal point for the crank

swing allows that intimate contact of the locking surfaces at 29 which is brought about first by the action spring 36 and then intensified by the chamber gas pressure and which causes the breech to be securely locked automatically by the 5 chamber gas pressure itself until the latter has fallen at least substantially to zero.

It will be observed that none of the pivots of the breech mechanism are called upon to resist the stresses set up by the discharge of the firearm, these stresses being taken by the faces at 27, 28, 29, and 30 so that apart from having the element of safety which is introduced by the gas-pressure locking action above referred to, the mechanism shown has the advantage that it may 15 be made of comparatively light compact members. Again the mechanism shown operates to produce a long opening movement of the breech block from but a comparatively short recoil 20 of but some $\frac{1}{4}$ inch serves to effect adequate breech opening for feeding an ordinary 0.30 calibre rifle cartridge (probably the longest military rifle cartridge made) into the chamber.

My invention is not limited to the particular 25 embodiment thereof herein shown and described, its scope being pointed out in the following claims.

I claim:

1. An automatic gun comprising, in combination, a barrel and receiver mounted to have recoil and counter-recoil or return movement relative to a stock, and recoil-operated breech closure mechanism including a block movable rectilinearly in the receiver, a link rearwardly of the 35 block and pivoted thereto, and a crank pivotally mounted on a crank pin in the receiver, rearwardly of the link and having pivotal connection with the latter, said block, link and crank forming substantially a unitary mass in their breech closing position and having a toggle-like opening and closing action, there being relatively large area abutments on the receiver and cooperating large area surfaces on the crank, the block and the link also having rearwardly of their interconnecting pivot cooperating pressure-transmitting locking surfaces of substantial area, and said crank pin having throughout the width of the crank a portion of less diameter than that of the pin receiving formations of the crank to afford 50 an operative clearance for the crank pin relative to the crank, main spring return means for the receiver and breech closure mechanism, and other spring-loaded means for assisting in opening said breech closure mechanism, said large 55 area abutments and surfaces on the block, link, crank and the receiver in cooperation with said crank pin structure being effective to transmit the breech pressure to the receiver independently of said crank pin and to insure intimate contact 60 of said pressure-transmitting and locking surfaces such that the breech closure mechanism is released for automatic opening only when the gas pressure has fallen substantially to zero.

2. An automatic gun according to the preceding 65 claim, wherein additionally the link and the crank are provided with interengaging arcuate pressure-transmitting surfaces of substantial area adjacent and concentric with their pivotal connection, and the block and the link also have 70 additional arcuate pressure-transmitting surfaces of substantial area adjacent and concentric with the pivotal interconnection of said block and link.

3. In a gun of the class described, a receiver, 75

breech mechanism including a reciprocatory block, a link pivoted at the rear of the block, and a crank pivoted in the receiver and having pivotal connection with said link, an actuator slidably mounted on the receiver, an actuator link connecting the crank and actuator, and one or more spring-pressed plungers carried by the actuator and engaging a fixed abutment thereby to energize the actuator during recoil movement of the parts, to assist in the breech-opening effort.

4. In a gun of the class described, a receiver, breech mechanism including a reciprocatory block, a link pivoted at the rear of the block, and a crank pivoted in the receiver and having pivotal connection with said link, an actuator slidably mounted on the receiver, an actuator link connecting the crank and actuator, and one or more spring-pressed plungers carried by the actuator and engaging a fixed abutment thereby to energize the actuator during recoil movement of the parts, to assist in the breech-opening effort, said actuator being provided with a main return spring housed in a portion thereof and bearing between a wall of the actuator and a portion of the receiver to assist in the counter-recoil or return movement of the receiver and barrel and to effect closure of the breech mechanism.

5. In a gun of the class described, a receiver, breech mechanism including a reciprocatory block, a link pivoted at the rear of the block, and a crank pivoted in the receiver and having pivotal connection with said link, an actuator slidably mounted on the receiver, an actuator link connecting the crank and actuator, and one or more spring-pressed plungers carried by the actuator and engaging a fixed abutment thereby to energize the actuator during recoil movement of the parts, to assist in the breech-opening effort, said actuator being provided with a main return spring housed in a portion thereof and bearing between a wall of the actuator and a portion of the receiver to assist in the counter-recoil or return movement of the receiver and barrel and to effect closure of the breech mechanism, and an auxiliary return spring acting substantially in parallelism with said main spring, bearing between the receiver and a fixed abutment on the stock.

6. In a gun of the class described, a receiver, breech mechanism including a rectilinearly reciprocatory block, a link pivoted at the rear of the block, and a crank pivoted in the receiver and having pivotal connection with said link, a firing pin carried by the block, and a striker and a sear therefor carried by said pivoted link, the block and the striker being provided with cooperating cam surfaces for cocking the striker during opening of the breech mechanism.

7. In a gun of the class described, a receiver, breech mechanism including a reciprocatory block, a link pivoted at the rear of the block, and a crank pivoted in the receiver and having pivotal connection with said link, a movable extractor at the fore end of the block, said pivotal connection of the block and the link comprising an annularly recessed fulcrum pin interconnecting said parts, a movable pin in the block engageable in said annular recess of the fulcrum pin to secure the latter, and a spring acting in one direction to engage said movable pin in said recess and oppositely to tension the extractor.

8. In a gun of the class described, a receiver, breech mechanism including a rectilinearly reciprocatory block, a link pivoted at the rear of

the block, and a crank pivoted in the receiver and having pivotal connection with said link, a firing pin carried by the block, and a striker and sear mechanism therefor carried by said pivoted link, said sear mechanism comprising a sear guided for movement transversely of and upon the link, spring means urging the sear toward striker-engaging position, and a pivoted lever engaging the sear and operable by trigger mechanism to release the sear from the striker.

9. In a gun of the class described, a receiver, breech mechanism including a reciprocatory block, a link pivoted at the rear of the block, and a crank pivoted in the receiver and having pivotal connection with said link, a slideable plunger housed in the crank and having an outer portion adapted to engage a solid part of the receiver, to limit and cushion the crank in its opening swing, a coil spring in the crank bearing at one end against said plunger, a removable member in the crank providing a seat for the opposite end of said spring, and releasable locking means for said member.

10. A gun in accordance with claim 3 wherein in the crank is mounted on a crank pin having throughout the width of the crank a portion of such distinctly and designedly less diameter than that of the pin receiving formation of the crank as to afford an operative clearance for the crank pin relative to the crank.

11. An automatic or semi-automatic gun of the class described, said gun having a receiver and a recoil-operative breech mechanism including a reciprocatory block, a crank pivoted in the receiver, a link between and pivotally connected with the block and the crank, there being cooperating relatively large-area abutments on the receiver and on the crank, and said crank having a crank pin held in the receiver, main spring return means for the receiver and breech mechanism, and other spring-loaded means for assisting in opening said breech mechanism, said crank pin having a distinct and designed clearance with respect to the crank whereby the breech pressure received by the crank is transmitted directly by the latter to the receiver through said abutments independently of said crank pin, the breech closure mechanism during the recoil being released for automatic opening only upon the gas pressure in the barrel falling substantially to zero.

12. In a gun of the class described, a receiver, breech mechanism including a reciprocatory block, a link pivoted at the rear of the block, and a crank pivoted in the receiver and having pivotal connection with said link, an actuator slidably mounted on the receiver, an actuator link connecting the crank and actuator, and actuator spring means operatively interposed between said actuator and a non-recoiling part, the construction and arrangement being such that said actuator and its spring means are energized by and during the initial recoil, and thereby are conditioned to initiate and assist in opening of the breech during the remaining recoil, when the gas pressure in the barrel has materially fallen.

13. In an automatic shoulder rifle operated by recoil, a slideable barrel and receiver, toggle-like breech mechanism including a block slideable on the receiver, a crank having pivotal connection with the receiver, and a link pivotally connecting the block and crank, an actuator link pivoted to said crank, an actuator slidably positioned on the receiver and pivotally engaged with said actuator link, and spring means for said actuator, said actuator and its spring means being energized by

initial recoil of the receiver to assist in opening the breech mechanism during the continued recoil.

14. In an automatic shoulder rifle operated by recoil, a slidable barrel and receiver, toggle-like breech mechanism including a block slidable on the receiver, a crank having pivotal connection with the receiver, and a link pivotally connecting the block and crank, an actuator link pivoted to said crank, an actuator slidably positioned on the receiver and pivotally engaged with said actuator link, and spring means for moving the actuator to initiate opening of the breech mechanism, said spring means arranged for operative loading during recoil of the receiver.

15. In an automatic shoulder rifle operated by recoil, a slidable barrel and receiver, toggle-like breech mechanism including a block slidable on the receiver, a crank having pivotal connection with the receiver, and a link pivotally connecting the block and crank, an actuator link pivoted to said crank, an actuator slidably positioned on the receiver and pivotally engaged with said actuator link, and spring means for moving the actuator to initiate opening of the breech mechanism, recoil of the receiver and closed breech mechanism serving to load said spring means for said opening action thereof upon substantial reduction of the gas pressure in the barrel.

16. In an automatic shoulder rifle operated by recoil, a slidable barrel and receiver, toggle-like breech mechanism including a block slidable on the receiver, a crank having pivotal connection with the receiver, and a link pivotally connecting the block and crank, an actuator link pivoted to said crank, an actuator slidably positioned on the receiver and pivotally engaged with said actuator link, said actuator adapted to travel with the receiver during initial recoil of the latter, and actuator spring means arranged to be loaded during said initial recoil, said actuator being moved by said spring means reversely relative to the receiver during further recoil of the latter thereby to break open said toggle-like breech mechanism.

17. In an automatic shoulder rifle operated by recoil, a slidable barrel and receiver, toggle-like breech mechanism including a block slidable on the receiver, a crank having pivotal connection with the receiver, and a link pivotally connecting the block and crank, locking formations of substantial area on said breech mechanism and corresponding abutment formations on the receiver, main spring return means for the receiver and breech mechanism, and other spring-loaded means for breaking open said breech mechanism, said barrel and receiver having a total recoil materially less than the length of the cartridge for the rifle, the pivotal connection of said crank and receiver comprising a pivot pin having a clearance formation adequate to provide for relative bodily movement between said parts, said breech mechanism remaining closed during a substantial initial portion of said total recoil of the barrel and receiver, and said crank pivot connection providing for intimate pressurelocked contact of said locking and abutment formations and for their rapid release by said spring-loaded means on dropping of the gas pressure, whereby complete opening of the breech mechanism is effected during the remainder of said short total recoil.

18. In an automatic shoulder rifle operated by recoil, a slidable barrel and receiver, toggle-like breech mechanism including a block slidable on the receiver, a crank having pivotal connection with the receiver, and a link pivotally connecting the block and crank, an actuator link pivoted to said crank, an actuator slidably positioned on the receiver and pivotally engaged with said actuator link, spring means for said actuator, said actuator and its spring means being energized by initial recoil of the receiver to assist in opening the breech mechanism during the continued recoil, the total recoil of the barrel and receiver being limited in length to a minor fraction of the length of the rifle cartridge, and said pivotal connection of the crank and receiver providing for relative bodily movement between said parts, whereby the breech opening action may be delayed, during said initial recoil, yet is completed during the full recoil despite the short total length of the latter.

19. In an automatic shoulder rifle operated by recoil, a recoiling receiver, breech mechanism in the receiver including a reciprocating block, a crank having pivotal connection with the receiver and a link pivotally connecting the block and crank, spring means for assisting the initial opening movement of the breech mechanism, means whereby said spring means is energized during the initial recoil and becomes operative during subsequent recoil, including a slidable part on the receiver and a link pivotally connecting it to the crank, and other spring means for returning the receiver and breech mechanism to closed position.

20. In an automatic shoulder rifle operated by recoil, a recoiling receiver, breech mechanism in the receiver including a reciprocating block, a crank having pivotal connection with the receiver and a link pivotally connecting the block and crank, spring means for assisting the initial opening movement of the breech mechanism, means whereby said spring means is energized during the initial recoil and becomes operative during subsequent recoil, including a slidable part on the receiver and a link pivotally connecting it to the crank, and other spring means for returning the receiver and breech mechanism to closed position, there being abutment lockings between the breech mechanism and the receiver, and the pivotal connection between the crank and receiver being arranged to afford relative bodily movement between said parts, for the purposes of intimate pressure-closed contact of said locking formations and of rapid release thereof in opening the breech mechanism.

21. In an automatic shoulder rifle operated by recoil, a recoiling receiver, breech mechanism in the receiver including a reciprocating block, a crank having pivotal connection with the receiver and a link pivotally connecting the block and crank, spring means for returning the receiver and for closing the breech mechanism, and other means, carried by the crank, for cushioning its opening swing, said means comprising a buffer element housed in the crank and having an outer face adapted to make angular sliding contact with a part which is fixed with respect to the receiver, and spring means urging said buffer element outwardly.
